METHOD AND APPARATUS FOR MAKING BOXES

Nels A. Anderson, Stockton, Calif., assignor to
Fibreboard Products, Inc., San Francisco, Calif.,
a corporation of Delaware

Application July 19, 1938, Serial No. 220,096

43 Claims. (Cl. 93—49)

My invention relates to the manufacture of fibreboard boxes of the type which are furnished to the trade in flat or collapsed condition for convenience in shipment and storage; which collapsed boxes are erected to extend the walls as they are needed for use.

It is among the objects of my invention to provide a method and apparatus for rapidly folding blanks into collapsed boxes.

Another object of the invention is to provide means for folding the blanks while the latter travel in a straight-line path through the machine.

A further object is to provide mechanism for folding the blanks without stopping the conveyor which advances the blanks through the machine.

Still further objects of the invention include the provision of improved means for feeding blanks into the machine; and for applying glue to the blanks; and for stacking the collapsed boxes.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

30 Referring to the drawings:

Figure 1 is a side elevational view of the head end of my box making machine, showing the blank feeding mechanism and the first folding units.

35 Figure 2 is a plan view of a blank from which the collapsed box is folded.

Figure 3 is a side elevational view of the intermediate portions of the machine, showing the gluing mechanism and subsequent folding means; 40 the left hand end of this view matching the right hand end of Figure 1.

Figure 4 is a detail vertical sectional view of the feed mechanism.

45 Figure 5 is a detail vertical sectional view of the folding unit.

Figure 6 is a side elevational view of the tail end of the machine, showing the stacker mechanism, the left hand end of this view matching the right hand end of Figure 3.

50 Figure 7 is a perspective of the collapsed box produced by my machine; and

Figure 8 is a similar view showing the box set up for use.

Figures 9 to 14, 16 and 17, are fragmentary 55 perspective views showing various steps in the

folding operation as the blank advances through the machine.

Figure 15 is a vertical sectional view of the gluing unit; and

Figure 18 is a detail vertical sectional view of the stacking unit.

In terms of broad inclusion, the collapsed box formed by the method and apparatus of my invention is folded from a blank having a bottom wall, marginal side and end walls, and end flaps 10 on the end walls. My method involves feeding the blank along a path; folding the leading and trailing marginal walls inwardly and turning portions of the latter walls back; folding the end flaps inwardly; and then folding the other marginal walls inwardly to position the infolded flaps over the back-turned portions of the first folded walls. Glue is preferably applied to the back-turned portions of the infolded walls before the other marginal walls are folded over. 20

Still in terms of broad inclusion, the machine of my invention includes conveyor means for advancing the blanks along a path through the machine; means for feeding blanks onto the conveyor; means for folding the blanks at various 25 stations along the path; means for applying glue to the blanks; and means for stacking the collapsed boxes.

In greater detail, and referring first to Figure 2 of the drawings, the collapsed box formed by the method and apparatus of my invention is folded from a blank of suitable sheet material, such as fibreboard, comprising a bottom portion 2 having marginal walls 3 and 4 foldably connected thereto along crease lines 6. For convenience in identifying the marginal walls, the opposing walls 3 are called side walls, and the other marginal walls 4 are called end walls. It is understood however that this is merely for purposes of illustration, since walls 3 may be arranged at the ends of a box. End flaps 7 are preferably provided, and are foldably connected to end walls 4 along crease lines 8. Diagonal crease lines 9 are also preferably arranged at the end portions of side walls 3 to form triangular 45 corner tabs 11.

The collapsed box produced by my machine is shown in Figure 7. In this condition of the box the side walls 3 have been folded inwardly over the bottom wall, with the corner portions 50 or tabs 11 turned back. End flaps 7 have been folded inwardly over the end walls, and the latter walls are folded inwardly to position flaps 7 over the back-turned portions 11 of the infolded side walls. Flaps 7 are glued to tabs 11 55

by a suitable adhesive 12. In this collapsed condition the box is flat, and may be stacked compactly for shipment and storage. Figure 8 shows the box when erected for use. This setting up 5 operation is a simple one, since the walls are merely pulled out to erected position.

As best shown in Figures 1, 3 and 6, the machine of my invention comprises a frame having side beams 13 along the bed of the machine 10 and supported adjacent the ends by legs 14. The drive mechanism is preferably located at the head end of the machine (Figure 1), and comprises a motor 16 connected to a shaft 17 by a chain drive 18. A suitable overload clutch, not shown, is 15 preferably mounted on shaft 17 to disconnect the motor, should a blank become jammed in the machine.

Blanks are fed into the machine from a chute 19 holding a supply stack 21 of the blanks. The 20 forward end of the chute is pivoted for adjustment on a cross rod 22, and the rear end is held up by a supporting rod 23. As better shown in Figure 4, the feed mechanism comprises feed roll 24 fixed for rotation with a shaft 26. A spring 25 pressed roller 27 is pivotally mounted to bear upwardly against the periphery of roll 24 to form a "bite" for engaging the blanks. The latter are delivered one at a time into this bite by means of a small planetary feed roll 28 journaled on the 30 main feed roll 24. Planet roll 28 is positively driven by a pinion 29 meshing a gear 31 loose on shaft 26 and held fixed by an arm 32 engaging a cross rod 33, so that when roll 24 is driven the pinion 29 rolls around gear 31 to rotate small 35 roll 28 in the same direction but at a higher rate of speed than the large feed roll 24.

Planet roll 28 projects slightly beyond the periphery of roll 24, and functions to engage a blank in stack 21 and advance it under roll 24. 40 A blank is thus fed forwardly each time roll 24 makes a revolution. A pivoted block 34 is preferably provided at the base of the chute for adjustment by a screw 36 to furnish a bearing surface for roll 28. Roll 28 is also preferably tired 45 with rubber to enhance its frictional engagement with a blank. The blanks are so stacked in chute 19 that they are fed sidewise into the machine; that is, with the edge of a side wall leading.

Feed roll shaft 26 is driven through a pair of 50 gears 37 from a lower shaft 38, which in turn is connected to a forward shaft 39 by a chain drive 41. Shaft 39 is driven from the main shaft 17 by a chain drive 42.

The blanks from the feed mechanism are carried forwardly by a conveyor or kick chain 43 having its forward sprocket fixed on shaft 39 and its rear sprocket loose on shaft 38. Kick chain 43 has lugs 44 spaced at intervals therealong for engaging the rear edges of the blanks. There 60 are preferably two of these kick chains, arranged parallel on the bed of the machine, for engaging the blank at spaced points, as shown in Figure 9. During the time that the blanks are being advanced by kick chains 43, the blanks are preferably held down by rails 46 under which the blanks slide. Suitable guide rails (not shown) are also 65 preferably provided along the bed of the machine for supporting and guiding the blanks.

Means are preferably provided for adjusting 70 the kick chains relative to the amount of their separation for accommodating blanks of different size. For this purpose plates 47 are arranged between the chain sprockets, with yoke connections 48 slidable on the shafts and embracing the sprockets, so that when the plates are

shifted the kick chains move with them. Plates 47 are adjusted simultaneously by screw rods 49 having reversely threaded portions and provided with squared ends 51 for receiving a hand crank. Idlers 52 are also preferably mounted on these 5 adjusting plates to keep the kick chains taut.

After reaching the end of the delivery conveyor provided by kick chains 43, the leading edge of a blank is caught between pairs of feed rolls 53 and 54 of the first folding unit. The lower 10 rolls 54 are freely journaled on a shaft 56 transverse of the machine bed. Upper feed rolls 53 are of C-shape, providing arcuate fingers 57 for engaging the blank. In fact, the finger portions 57 are the only parts of the upper rolls which 15 are effective for engaging the blank; point 58 being the first to engage the blank. This point of engagement is such that the trailing ends of fingers 57 lie along the base portions of the trailing side wall and end tabs, when the roll has turned 20 enough to bring these finger ends down, see Figures 5 and 10.

Feed rolls 53 are fixed on a shaft 59 connected for rotation with shaft 39 through a train of gears 61. Shaft 59 is urged down by spring 62 25 bearing against the journal blocks of the shaft, to resiliently press the feed rolls against the blank. The peripheral speed of feed rolls 53 is preferably somewhat greater than the speed of delivery chain 43, so that the blank is pulled 30 ahead of the chain lugs 44 during the folding operation. By speeding up the blank at this point, the time lost in the folding station is made up.

Means are provided at the first folding station for folding the trailing side wall 3 up and inwardly over the bottom wall; and means are also provided for simultaneously folding the trailing end flaps 7 inwardly over the end walls 4. 40 As shown in Figures 1, 5 and 10, a series of folding elements or arms 63 are fixed on shaft 56; which shaft is turned back and forth to oscillate the arms by means of a segment rack 64 engaging a pinion on the shaft. Rack 64 is actuated by a cam 66 on a shaft 67 which is driven 45 from shaft 39 through suitable gears 68. Oscillation of arms 63 is so timed that they rotate up to fold over the trailing side wall and the end tabs while roll fingers 57 are still engaged with the blank. That is, the wall and flaps are folded over the ends of fingers 57 to the positions shown in Figure 10 before the fingers rotate out of engagement with the blank.

Means are also provided for turning back the triangular tab portions 11 of the trailing side wall. As best shown in Figure 10, a pair of fixed rods 71 are suitably fastened to the frame of the machine, and are arranged to be engaged by tabs 11 to turn them back when wall 3 is folded up by arms 63. Rods 71 continue along the bed of 60 the machine and thus serve to hold tabs 11 down after they are turned back. Suitable bars 72 are also provided for pushing down the infolded wall and flaps, and for holding the latter in their folded positions. These pivoted bars are normally held up out of the way, and are then lowered after the folding operation by means of slide rods 73 actuated by levers 74 from a cross shaft 76. Levers 74 are rocked by a linkage 77 connected between shaft 76 and a cam 78 mounted 70 on shaft 59. Spring 79 serves to hold the follower roller of the linkage against the cam.

As feed rolls 53 continue to turn, their fingers 57 rotate away from the lower feed rolls 54 and release the pressure on the blank. At this time 75

the blank ceases forward movement and fingers 57 rotate out of engagement with the infolded wall and flaps. Bars 72 now come down to complete downward folding of the wall and flaps, 5 and arms 63 rotate back out of the way to clear the next incoming blank. The slight pause in the forward movement of the blank at this folding station does not delay the progression of the blanks through the machine, because of the 10 speeding up of the blank by feed rolls 53 and 54 prior to the folding operation.

Means are provided for further advancing the blank through the machine. A second conveyor is provided, comprising a pair of kick chains 81 15 having lugs 82 which come up into engagement with the blank to continue forward movement of the latter. The conveyor or kick chains 81 are relatively long ones and serve to advance the blank through the remaining portions of the 20 machine. These conveyor chains have rear sprockets freely journaled on shaft 56 and forward drive sprockets fixed on a shaft 83 rotated by a pair of drive chains 84 running from the drive shaft 39 of the first conveyor to a shaft 85 25 at the center of the machine and then forward to the front shaft 83. There are preferably two sets of drive chains 84, one set along each side of the machine, paralleling the kick chains. Instead of driving with chains 84, suitable shafts 30 could be journaled longitudinally of the machine and beveled gears provided at the various cross shafts. The kick chains 43 and 81 of both conveyors run at the same speed. Kick chains 81 of the second conveyor are also mounted for adjustment by screws 86, in the same manner as described for the first conveyor; and idlers 87 are provided to keep the chains taut.

Means are provided at a second folding station for folding the leading side wall 3 inwardly over 40 the bottom wall; and means are provided for simultaneously folding the leading end flaps 7 inwardly over the end walls. As shown in Figures 1, 5, 11 and 12, a series of oscillating arms 88 are fixed on a transverse shaft 89 mounted 45 above the bed of the machine ahead of the first folding unit. These arms have arcuate fingers 91 for engaging the blank above supporting rolls 92 freely journaled on a shaft 93; the engagement of the forward ends of the fingers being 50 along the fold lines at the base of the wall and flaps.

Shaft 89 is slidable vertically in bearings urged 55 downwardly by springs 94 to hold arms 88 normally down in engagement with the blank. As the leading fold lines pass over rolls 92 the arms are lowered to engage fingers 91 with the blank. This lowering is accomplished by a linkage comprising levers 96 connected to the shaft mounting and actuated by a bell crank 97 controlled 60 by a cam 98 on shaft 59.

As soon as fingers 91 engage the blank, arms 65 88 swing forwardly in time with the blank movement. The forward swinging is effected by rocker arm 99 fixed on shaft 89 and connected by link 101 to a bell crank 102 actuated by a cam 103 on shaft 59. Simultaneous with the forward movement of arms 88 suitable levers 104 fixed on a shaft 106 swing up to raise the wall and flaps to the positions shown in Figure 11. 70 Levers 104 are controlled by the same cam 103 which oscillates arms 88, by means of a second rocker arm 107 fixed on shaft 89 and connected to crank 108 on shaft 106 by link 109.

As the blank continues to advance, the leading wall 3 and flaps 7 are folded inwardly by

reason of their riding under the folding levers 104, as shown in Figure 12. At this time the triangular tabs 11 of the side wall are turned back by the fixed rods 71, these rods being the same ones which turned back the tab portions of the trailing wall. After reaching the position shown in Figure 12, arm fingers 91 are lifted by cam 98, and the blank continues its forward motion under the pushing action of kick chain lugs 82. Final downward folding of the wall and flaps is accomplished by the sliding of these parts under levers 104. When the entire blank 10 has cleared the second folding unit, cam 103 15 operates to swing arms 88 back and depress levers 104 for receiving the next incoming blank. 13

From the second folding station the partially folded blank passes to the gluing unit. During this period of progression through the machine, the folded portions of the blank are held down by suitable rails mounted on the machine frame. 20 Figure 13 shows a center rail 111 bearing down on side walls 3, and pairs of rails 112 and 113 bearing down on flaps 7 and the outer corner portions of the back-turned tabs 11. This arrangement of rails 113 leaves the major portions 25 of tabs 11 free for application of glue 12. Side rails 112 and 113 are preferably adjustably mounted to take care of different size blanks.

As shown in Figures 3 and 15, the gluing unit 30 comprises a gluing roll 114 mounted on shaft 115. There are a pair of these rolls, and each has glue pads arranged to apply a suitable cement to the back-turned portions 11 of the blank. A supporting roll 116 is provided on shaft 85 under each gluing roll; and the whole 35 shaft assembly is mounted on pivoted arms 117 pressed upwardly by springs 118 against a suitable adjustable stop. By this arrangement the supporting rolls 116 resiliently press the blank against the glue pads of rolls 114. The upper 40 limit of supporting rolls 116 is so adjusted however that the rolls do not contact the glue pads when no blank is passing between them. Glue is applied to each gluing roll by a transfer roll 119 45 engaging supply roll 121 running in the glue pot 122. A glue control roll 123 is also provided and is journaled in eccentric bearings 124 for adjusting its periphery relative to the transfer roll to control the thickness of glue on the latter and thereby regulate the amount of glue transferred to gluing roll 114. These various rolls of the gluing unit are also arranged in pairs on suitable shafts, and are driven by suitable gears 126 from shaft 85; the glue control rolls 123 being driven from the supply roll shaft by a chain 50 127.

Means are provided for shifting the transfer rolls out of engagement with gluing rolls 114 at such times when no blank is coming into the gluing unit, so as to prevent glue from building 55 up on the gluing rolls. Transfer rolls 119 are mounted on a bracket 128 slidably supported at its forward end and pivoted at the rear end to an arm 130 fixed on shaft 129. This bracket also supports supply rolls 121 and control rolls 60 123. The whole bracket unit is shifted back by a cam 131 on shaft 115, operating through an arm 132 and pull bar 133 hooked to a depending lever 134 on shaft 129.

Means are also provided for preventing the 65 bracket from shifting back when a blank is passing through the gluing unit. For this purpose a finger 135 linked to bar 133 is pivotally mounted to lie in the path of movement of the blank so that a blank lifts the finger to raise bar 133 70 75

out of hooked engagement with lever 134. Bar 133 then merely shifts back and forth without retracting the transfer rolls. Figure 13 shows the blank as it leaves the gluing unit, with glue 5 deposits 12 on the back-turned tabs 11.

From the gluing unit the blank passes through a third folding device, comprising a pair of triangularly-shaped bars 137 arranged along the bed of the machine with a lower edge overlying 10 the fold lines along the base portions of end walls 4. See Figure 14. These bars are supported at the rear ends only by supports 138, so that the bars project forwardly freely; and the bars are preferably adjustable transversely of 15 the bed to accommodate blanks of different size. The end walls are folded up over bars 137 by rods 139 suitably fixed on the machine by adjustable supports 140. These rods are shaped to curve 20 from a position alongside the bar to a position over the top of the bar. The rods thus lift the end walls and fold them inwardly over the bars as the blank slides along the rods and bars. In order to give a smooth folding action to the device, the outer surface of each bar 137 preferably 25 follows a helical curve.

The sloping inner surfaces of the bars serve to keep tabs 11 from folding up, and the triangular shape of the bars provides lower edges for bearing down against the fold lines without 30 smearing the glue. Figure 16 shows a blank as it approaches the ends of folding bars 137, and also shows rails 141 under which the folded blank passes. These rails are suitably mounted on the machine, also for adjustment, and serve to force 35 the end walls down to press infolded flaps 7 into sealing engagement with back-turned tabs 11. Figure 17 shows the final folded or collapsed position of the box.

Means are also provided for stacking the collapsed boxes. As shown in Figures 6 and 18, the stacking unit comprises a pair of feed rolls 142 and 143 for delivering a box from the end of conveyor 81 into stack 144. Lower roll 142 is driven from shaft 83 by a drive chain 146, and upper 40 roll 143 is freely journaled on a shaft held at each end by a pivoted arm 147 urged down by spring 148. Feed rolls 142 and 143 are preferably arranged in pairs for engaging the edges of a blank. The boxes in stack 144 are inclined in overlapping 45 relation and the newly folded boxes are delivered under the bottom of the stack.

Means are provided for lifting the stack when a new box is added. A hooked arm 149 is pivoted to a lever 151 on shaft 152, and this shaft is 50 rocked to lift the arm by linkage 153 connected to a cam 154 on shaft 156; the latter being driven from shaft 83 by chain 157. Hook 158 at the bottom of arm 149 engages the edge of the bottom carton, so that the rear end of the stack is lifted 55 when arm 149 goes up. After a new box has been shoved under the stack, arm 149 is pulled back by link 159 actuated through shaft 161 and linkage 162 from cam 163 on shaft 156. After being pulled back, arm 149 is lowered by cam 154 and 60 pushed forward by cam 163 to engage the new bottom carton; following which the arm is again elevated to lift the stack.

The collapsed boxes are pushed under the stack by a reciprocating plate 164 actuated by a rack 70 and segment 166 driven by a crank arm 167 on shaft 156. Plate 164 carries a spring pressed dog 168 for engaging the trailing edge of the box after it leaves feed rolls 142 and 143. Stack 144 is fed forwardly step-by-step by a conveyor 169 75 moved intermittently by a link 171 connected

with crank arm 167 and working through a suitable one-way clutch 172. The boxes in the stack are held down to insure tight cementing of the glued surfaces by a pressure belt 173 on a frame 5 174 supported at the forward end only by a vertical guide way 176. Belt frame 174 is preferably jointed at 177 to facilitate lifting the front end of the stack.

In order to prevent the stacker unit from operating when no boxes are being fed into it, a suitable clutch (not shown) is preferably provided on shaft 156 for cutting out the mechanism. This clutch is engaged to operate the stacker unit by a linkage 178 lifted by a finger 179 when a blank approaches feed rolls 142 and 143. 15

I claim:

1. The method of making a box from a blank having walls foldably connected to a main body panel, which comprises feeding the blank along 20 a path, folding the trailing and leading walls inwardly over said main body panel and turning triangular portions of each of said leading and trailing walls back upon itself while said blank is moving in said path and then folding other walls inwardly over the back-turned portions of 25 said infolded walls.

2. The method of making a box from a blank having marginal walls foldably connected to a main body panel, which comprises moving the 30 blank to a folding station, folding a marginal wall at said station inwardly over said main body panel along a line transverse to the direction of motion and turning portions of said marginal wall back upon itself, moving the blank to a second folding station, and folding a second marginal 35 wall at the second station inwardly over said main body panel along a line transverse to the direction of motion and turning portions of said second marginal wall back upon itself.

3. The method of making a box from a blank 40 having marginal walls foldably connected to a main body panel, which comprises moving the blank to a folding station, folding a marginal wall at said station inwardly over said main body panel along a line transverse to the direction of motion and turning portions of said marginal wall back upon itself, moving the blank to a second folding station, and folding a second marginal 45 wall at the second station inwardly over said main body panel along a line transverse to the direction of motion and turning portions of said second marginal wall back upon itself, and then folding other marginal walls inwardly over the back-turned portions of said infolded walls.

4. The method of making a box from a blank 50 having side and end walls foldably connected to a bottom panel and having end flaps foldably connected to the end walls, which comprises moving a blank along with said side walls transverse to the direction of motion, folding the trailing side wall inwardly over the bottom panel and turning triangular portions of said trailing wall back upon itself, folding the trailing end flaps inwardly upon the end walls, folding the leading side wall inwardly over the bottom panel and turning triangular portions of said leading wall back upon itself, folding the leading end flaps inwardly over the end walls, and then folding the end walls inwardly to position the infolded end flaps over the back-turned portions of the infolded side walls, 55 after applying adhesive to one of the meeting surfaces of said infolded flaps and back-turned portions.

5. A machine for making a box from a blank 60 having marginal walls foldably connected to a 65

main body panel, comprising means for moving the blank through the machine, means for folding the trailing marginal wall inwardly over said main body panel along a line transverse to the direction of motion and for turning portions of said trailing wall back upon itself, and means for folding the leading wall inwardly over said main body panel along a line transverse to the direction of motion and for turning portions of said leading wall back upon itself.

6. A machine for making a box from a blank having marginal walls foldably connected to a central panel, comprising means for moving the blank through the machine, means for folding the trailing marginal wall inwardly over said central panel along a line transverse to the direction of motion and for turning portions of said trailing wall back upon itself, means for folding the leading wall inwardly over said central panel along a line transverse to the direction of motion and for turning portions of said leading wall back upon itself, and means for folding other marginal walls inwardly over the back-turned portions of said infolded walls.

7. A machine for making a box from a blank having side and end walls foldably connected to a bottom panel and having end flaps foldably connected to the end walls, comprising means for moving the blank to a folding station, means at said station for folding a side wall inwardly upon the bottom panel along a line transverse to the direction of motion and for turning portions of the side wall back upon itself, means at said station for folding the adjacent end flaps inwardly upon the end walls, means for moving the blank to a second folding station, means at the latter station for folding another side wall inwardly upon the bottom panel along a line transverse to the direction of motion and for turning portions of said side wall back upon itself, and means at said second station for folding the adjacent end flaps inwardly upon the end walls.

8. A method of making boxes with all the walls folded inwardly which includes preparing box blanks with the walls foldably connected to the main body, one opposite pair of said walls having triangular portions defined by diagonal fold lines on each end thereof, the other opposite pair having sealing flaps foldably connected at each end, moving said blanks with the last named walls parallel to the direction of motion, and, while folding the rearward wall forwardly and the forward wall rearwardly, folding the respective triangular portions thereof reversely, and after folding the rearward sealing flaps forwardly and the forward sealing flaps rearwardly, applying adhesive between the triangular portions and the sealing flaps, folding the remaining opposite pair of walls inwardly to overlie the main body and thereafter applying pressure to bring about adhesion between the triangular portions and a portion of the sealing flaps.

9. A method of making infolded knock down boxes from blanks with one pair of opposite walls having angular lines of fold defining triangular portions therein, and the other pair of opposite walls having sealing flaps hingedly connected thereto, which includes moving said blanks along with said first mentioned pair of walls transverse to the direction of motion, and folding said first mentioned walls inwardly while folding the triangular portions of said first mentioned walls reversely to the direction of folding of the respective walls to which said triangular portions are attached, and also folding the sealing flaps in to

overlie the walls to which they are articulated, applying adhesive to one of the meeting surfaces of the flaps and triangular portions and, while retaining all folded portions in folded position, folding in the remaining pair of opposite walls to overlie previously folded walls and portions thereof as well as the main body, and thereafter applying pressure to secure adhesion.

10. The method of making infolded knock down boxes from blanks having one pair of opposite walls with angular lines of fold defining triangular portions therein, and the other pair of opposite walls having sealing flaps hingedly connected thereto, which comprises moving said blanks along, with said last named walls parallel to the direction of motion, folding in said first named walls to overlie the main body panel with the triangular portions thereof folded back upon said first named walls, and after having likewise folded inwardly said sealing flaps, retaining all folds in folded position, applying adhesive to one of the contacting surfaces of angularly folded portions and sealing flaps thereof, folding inwardly said last named walls and applying pressure thereafter to secure adhesion between said contacting surfaces of said angular portions and sealing flaps.

11. The method of making infolded knock down boxes which includes folding in all four walls while the blank is conveyed in one position in relation to its direction of motion, the infolding of one pair of opposite walls being accompanied by the folding in a reverse direction of triangular end portions of said walls whereby said portions overlie the walls of which they form a part, and the infolding of the remaining pair of opposite walls being preceded by the folding in of corner flaps articulated thereto.

12. The method of making a box from a blank, which comprises moving the blank along a path, folding a wall of the blank forwardly in the direction of motion along a line of fold transverse to the direction of motion, turning a part of said wall in the opposite direction, and folding another wall of the blank in a direction transversely of the blank travel.

13. The method of making a box from a blank, which comprises moving a blank along a path, folding a trailing wall of the blank forwardly in the direction of motion along a line of fold transverse to the direction of motion, turning a portion of said trailing wall in the opposite direction, folding a leading wall of the blank in said opposite direction, and turning a portion of the leading wall in the direction of blank travel.

14. The method of making infolded knock down boxes which comprises moving a blank having articulated portions, infolding one pair of opposite articulated portions along lines transverse to the direction of motion of the blank, and infolding the other pair of opposite articulated portions along lines parallel to the direction of motion of the blank, said first mentioned infolding including the diagonally articulated parts of certain of said portions, and said last mentioned infolding being preceded by the folding in of sealing flaps articulated to certain of said portions, all during the continued motion of said blank.

15. In a machine for making infolded knock down boxes from cut and creased blanks having a main body panel, one pair of opposite walls having angular lines of fold therein defining triangular portions and the remaining pair of opposite walls having sealing flaps articulated to the end thereof, means for moving said blanks

along in timed relation with said first mentioned pair of walls transverse to the direction of motion, means for infolding said first-mentioned walls to overlie the main body panel and means 5 for folding said triangular portions back upon the outside thereof, means for folding sealing flaps in to overlie the walls to which they are articulated, means to apply adhesive to one of the meeting surfaces of said folded flaps and said folded triangular portions, subsequent means to fold inwardly said remaining pair of opposite walls, and means for applying pressure to assure adhesion.

16. In a folding and gluing machine, means 15 for advancing a blank, means for folding a forward wall rearwardly of the direction of motion along a line transverse to the direction of motion, and means for folding in a reverse direction triangular portions thereof, means for folding 20 forwardly a trailing wall along a line transverse to the direction of motion, and means for folding backwardly triangular portions thereof, and means to retain said folded walls and triangular portions in folded position during the 25 further travel of said blank.

17. In a machine for making a box from a blank, means for conveying a blank in a unidirectional path, means along said path for folding a wall of the blank along a line of fold transverse 30 to said path and turning part of said wall back upon itself along an angular line, and means along said path for folding another portion of the blank over said backwardly turned part.

18. In a machine for making infolded knock 35 down boxes from cut and creased blanks having a main body panel, one pair of opposite walls having angular lines of fold therein defining triangular portions and the remaining pair of opposite walls having sealing flaps articulated to 40 the ends thereof, means for conveying said blanks with said first pair of walls transverse to the direction of conveyance moving means acting upon the outer surface of the first pair of walls to effect an infolding action on said walls, 45 coordinated with other means acting upon the inner surface of triangular end portions of said walls whereby upon completion of said first named action said walls are folded in over the main body portion and said triangular end portions are folded back upon said walls.

19. In a folding and gluing machine, means for advancing the blank, means for folding inwardly one pair of opposite walls along lines transverse to the direction of motion of the 55 blank, and means to hold back the ends of said walls as said walls are being folded.

20. In a machine of the character described, means for conveying a blank with one pair of opposite walls transverse to the direction of travel and having diagonal lines of fold defining portions at the ends thereof, means for folding said walls inwardly and means for folding said portions reversely along the said diagonal lines.

21. The method of making infolded knock 60 down boxes which includes moving a blank and folding a pair of opposite walls inwardly along lines transverse to the direction of motion of the blank as end portions of said walls are folded 65 reversely of the direction of folding of respective walls.

22. The method of making a box from a blank, which comprises moving the blank, folding inwardly one pair of opposite walls along lines 70 transverse to the direction of motion and simul-

taneously folding portions of said walls reversely along diagonal lines.

23. In a machine for forming boxes from blanks having a main panel and a pair of opposite walls articulated thereto along lines transverse to the movement of said blank in said machine, primary movement means acting upon an unfolded portion of said blank, folding means acting upon said blank to fold over at least one of said wall portions, and secondary movement 10 means for said blank acting upon a folded portion thereof to move said blank during the folding of another portion thereof.

24. In a machine for forming boxes from blanks having a main panel and a pair of opposite walls articulated thereto along lines transverse to the movement of said blanks in said machine, means to impart to said blanks a movement sequence in said machine, means moving in 15 timed sequence therewith for folding over said walls on said transverse lines, fixed turn back 20 means to engage triangular end portions of said walls during said folding and fold said portions in the opposite direction, and means acting on 25 said blank to prevent transverse buckling thereof during said folding operations.

25. In a machine for making knock down 30 boxes, two independent conveying means acting successively to move a blank along in one direction of motion, the first of said means introducing the blank into a primary folding operation, and the second of said conveying means engaging said blank on a folded portion, and means for effecting secondary folding operations on 35 other blank portions.

26. In a machine for making knock down 40 boxes, two independent conveying means acting successively to move a blank along in one direction of motion, the first of said means introducing the blank into primary folding operations, 45 said primary folding operations including folding along lines transverse the direction of motion, and the second of said means engaging said blank on a folded portion as secondary folding operations on other blank portions are effected, 50 said secondary operations including folding along lines parallel to the direction of motion.

27. In a machine for making knock down 55 boxes, means for moving along a blank with one pair of walls transverse to the direction of motion, said walls having diagonal lines of fold defining end portions thereof, moving means to fold said walls inwardly, and stationary means so shaped and positioned as to engage the end portions and hold same back against the movement of said walls as said walls are being folded.

28. In a machine for making knock down 60 boxes, means for moving the blank, moving means for folding a wall on a line transverse to the direction of movement, in combination with 65 stationary means to deflect backwardly along a diagonal line an end of said wall as the wall is folded.

29. In a machine for making knock down 70 boxes, means for conveying a blank with one pair of opposite walls articulated along lines transverse to the direction of motion thereof and having triangular portions at the ends thereof, means to fold said walls inwardly and means to deflect 75 said portions backwardly as said walls are folded inwardly.

30. A process of making boxes from blanks having a main panel and side and end walls, said end walls having sealing flaps, which comprises moving the blank in one direction of motion and 75

- by folding means, during said motion, folding over upon the main panel said side walls along fold lines transverse to the direction of motion of the blank, and folding back on said side walls 5 triangular end portions of said walls by means of fixed folding means, and causing folding means to hold down the folded portions of said walls during continued motion of said blank until said folded portions pass beneath a fixed hold down 10 extending in said direction of motion.
31. A process of making boxes from blanks having a main panel and side and end walls, said end walls having corner flaps, which comprises moving the blank in one direction of motion and by folding means, during said motion, folding over 15 upon the main panel said side walls along fold lines transverse to the direction of motion of the blank, and folding back on said side walls triangular end portions of said walls by means of fixed 20 folding means, and causing folding means to hold down the folded portions of said walls during continued motion of said blank until said folded portions pass beneath a fixed hold down extending in said direction of motion, also folding over 25 said end flaps, and while so maintaining said walls in folded condition, during a continuation of said motion, folding over the other pair of opposite walls with the interposition of adhesive between the said end flaps and the said triangular 30 portions.
32. In a machine for making knock down boxes, blank moving means, means to fold a blank wall upwardly along a line transverse to the direction of blank movement, a shaped stationary 35 member to deflect backwardly along a diagonal line one end portion of said blank wall so moved upwardly thereagainst, said stationary member thereafter serving to retain said wall and portion in folded position.
33. In a machine for making knock down boxes, in combination with folding means, moving means to grip unfolded blank portions as the forward wall is folded backwardly along a line transverse to the direction of motion of the blank and the 40 rearward wall is folded forwardly along a line transverse to the direction of motion of the blank.
34. In a machine for forming boxes from blanks, having a main panel and a pair of opposite walls articulated thereto along lines transverse to the movement of said blank in said machine, means for moving said blank, moving folding means acting on said blank to fold over said walls on said transverse lines, and moving means 45 effective during the operation of said folding means to grip said blank on other portions than on said walls to prevent disalignment of said blank.
35. In a machine for forming boxes from blanks 50 having a main panel and a pair of opposite walls articulated thereto along lines transverse to the movement of said blank in said machine, means for moving said blank, moving folding means acting on said blank to fold over said walls on 55 said transverse lines, and moving means effective during the operation of said folding means and engaging said blank elsewhere than on said walls and located so as to be effective during the folding of both of said walls to prevent disalignment 60 of said blank and to assist in moving said blank.
36. In a machine for making knock down boxes, means for moving a blank along in one direction, and means for making six distinct folds transverse to the direction of motion, two of said folds 65 being along lines defining opposite walls and four 70 of said folds being along lines defining corner flaps.
37. In a machine for making knock down boxes from blanks having slots on two opposite edges defining three distinct panels at each of said edges comprising a central wall and adjoining sealing flaps, means for advancing said blanks with said edges transverse to the direction of motion, and means for folding the leading three of said adjoining panels inwardly and rearwardly 10 of the direction of motion at one of said edges, and means for folding the trailing three of said adjoining panels inwardly and forwardly of the direction of motion at the opposite edge.
38. In a machine for making knock down boxes 15 from blanks having slots on two opposite edges, defining three distinct flaps at each of said edges comprising a central wall and adjoining sealing flaps, means for advancing said blanks with said edges transverse to the direction of motion, and means for folding the leading three of said adjoining flaps inwardly and rearwardly of the direction of motion at one of said edges, and means for folding the trailing three of said adjoining flaps inwardly and forwardly of the direction of motion at the opposite edge, the infolding of said central walls including a reverse folding of the triangular corner portions thereof.
39. In a machine for making knock down boxes 20 from blanks having slots on two opposite edges, defining three distinct flaps at each of said edges comprising a central wall and adjoining sealing flaps, means for advancing said blanks with said edges transverse to the direction of motion, and means for folding the leading three of said adjoining flaps inwardly and rearwardly of the direction of motion at one of said edges, and means for folding the trailing three of said adjoining flaps inwardly and forwardly of the direction of motion at the opposite edges, the infolding of said 25 central walls including a reverse folding of end portions thereof along diagonal lines, and thereafter folding in the remaining pair of walls parallel to the direction of motion.
40. In a machine for making knock down boxes 30 from blanks having slots on two opposite edges defining three distinct panels at each of said edges comprising a central wall and adjoining sealing flaps, means for advancing said blanks with said edges transverse to the direction of motion, and means for folding the leading three of said adjoining flaps inwardly and rearwardly of the direction of motion at one of said edges, and means for folding the trailing three of said adjoining flaps inwardly and forwardly of the direction of motion at the opposite edge, and after 35 folding end portions of said central walls reversely to lie facing upwardly on said infolded walls, applying adhesive to one of the meeting surfaces of said triangular portions and said infolded sealing flaps and thereafter folding in the remaining pair of walls.
41. In a machine for making knock down boxes 40 from blanks having a main body panel, one pair of opposite walls having diagonal lines of fold defining triangular end portions thereof and the remaining pair of opposite walls having corner flaps articulated thereto, means for moving said blanks along with said first mentioned walls transverse to the direction of motion, and moving means to fold said walls inwardly, stationary means to fold said triangular end portions outwardly, and other moving means to fold said corner flaps inwardly to overlie the walls to which they are articulated.

42. In a machine for making knock down boxes, moving means adapted to fold in one pair of opposite walls along lines transverse to the direction of motion of a blank and separate moving means to fold in two pairs of opposite sealing flaps along lines transverse to the direction of motion of the blank.

43. In a machine for making a box from a

blank movable along a path, a pair of elements spaced along said path and over which opposite marginal portions of the blank may be folded, means for moving both of said elements in the direction of blank movement, and means for moving one of said elements in the opposite direction.

NELS A. ANDERSON.
